The new design for an orthotic shoe insert, as shown and described.

DESCRIPTION

FIG. 1 is a top perspective view of an orthotic shoe insert showing my new design;

FIG. 2 is a bottom perspective view thereof;

FIG. 3 is a top plan view thereof;

FIG. 4 is a side elevational view of a first side thereof;

FIG. 5 is a front elevational view thereof;

FIG. 6 is a side elevational view of a second side thereof;

FIG. 7 is a rear elevational view thereof; and,

FIG. 8 is a bottom plan view thereof.

FIG. 1

FIG. 2

FIG. 3

FIG. 5

FIG. 7

FIG. 8
